MEDICATION APPLIANCE

Michael E. Demsey, Cleveland, Ohio

Application August 12, 1939, Serial No. 289,886

10 Claims. (Cl. 128—249)

5 My invention pertains to a medication appliance and more particularly to a combination with a syringe of a cup-shaped member adapted for detachable connection around the top of a bottle (preferably exteriorly though alternatively interiorly) and of another cup-shaped member enclosing the first and as an eye guard intended to be pressed against the skin around an inflamed or infected area—the whole thing being 10 a unitary structure.

15 Experience with the use of eye cups, to be pressed against the face around an eye while partially filled with a medication fluid for bathing any affected part of the enclosed tissue, has taught their inconvenience and attendant waste 20 of excess fluid. Conventional eye droppers are often ineffective if wielded by unskilled hands and incidentally wasteful either because of an unsteady or misdirected manipulation or because 25 of nervousness on the part of the patient upon approach of the discharge tip.

30 According to one form an eye guard provided with venting means, preferably one or more lateral apertures between the bottom and rim of the 35 guard, has a syringe attached to and adapted to discharge dropwise not only through the guard, but through a guard-enclosed conventional screw cap for a bottle. Another form comprises a yieldable stopper having its one side intended 40 to wedge in the neck of a bottle and its other side frictionally inserted into a collapsible rubber bulb. Optionally a glass nozzle may line the stopper-functioning side of the stopper. For individual home use a small amount of the medication fluid (sometimes a thin salve) is segregated 45 in the screw cap by inversion of the bottle, then a few drops syphoned into the syringe, the surplus permitted to flow back into the bottle and thereafter the guard pressed around the eye and 50 the few drops ejected with certainty, with safety and without waste.

45 A general object has been inexpensively to combine several units hitherto separated, whereby to facilitate use, to provide a convenience 55 serving novelty of compact and unitary structure as well as to improve upon performance of the required treatment, because an inversion of the entire assembly may segregate the small amount required in the hollow cap preparatory 60 to syphoning it into the syringe reservoir while only a very short, if any, nozzle on the latter is needed. The unitary assembly of the three parts insures proper connection thereof, and prevents 65 displacement or loss while collectively adapted to be carried by, as a closure for the bottle.

60 It is to be realized that the scope of my invention comprehends many equivalent constructions. The showings of the drawing and the description are merely specific exemplifications of

a plurality of mechanical embodiments and arrangements.

Adverting to the drawing:

Figure 1 is a vertical section of an all-feature-including embodiment of my invention applied 5 to a fragmentary neck of a bottle.

Figure 2 is a top plan view of Figure 1.

Figure 3 is a bottom plan view of Figure 1.

Figure 4 is a view, similar to Figure 1, of a 10 modified form of my invention.

Figure 5 is a broken, vertical sectional view of another modification.

15 A bottle neck 1 is fashioned with external screw threads 2. A screw cap 3 of concavo-convex form is formed with a conically surfaced hole 4 located centrally of the head portion of the cap, and the latter comprises a depending annular flange 5 which is interiorly fashioned with complementary screw threads 6 adapted for feasible cooperation with the bottle-neck threads 2. 20

Enveloping the cap 3 is a larger, concavo-convex eye-guard 7 provided with a flat central area 8 conforming to and secured in any appropriate manner to the outer or upper side of the head 25 of the cap 3. The area 8 is provided with a hole defined by a complementarily surfaced wall 9. Opposite sides of the guard are shown provided with venting apertures 10 which are intended to preclude air-pressure resistance to dropwise discharge when the guard is tightly pressed against 30 the face and may be as large as possible without lessening the rigidity of the guard in order to economize in the material of which it may be composed, for instance, a suitable plastic, glass 35 or metal, or hard rubber. The lower annular or elliptical margin of the guard is shown curled at 11 for comfort and safety when pressed against the face around a human eye.

35 A nipple 12 includes a head 13 fitted within the cap 3. The nipple may be of rubber or other 40 yielding material and includes also an upward extension 14, exteriorly defined by a conical surface, which is wedge-seated in the margins of the openings 4 and 9 in the cap and guard respectively. Frictionally enclosing in turn a projecting upper end of the extension 14 is a rubber bulb 15 which also seats against the flat, annular portion of the guard and which is intended 45 to serve the function of a syringe or dropper. Optionally, a glass or lining tube 16, of any 50 other suitable material may be inserted through the nipple and flanged at 17 interiorly of the bulb.

55 A convenient unitary assembly is thus provided, with the somewhat perishable bulb, if of rubber, readily replaceable by mere loosening of the close mechanical fit. When detached from a bottle a small amount of the medicant may be supplied to the cap while the bulb is collapsed whereupon release of the latter will syphon the 60

5 segregated medicant into the bulb preparatory to dropwise discharge when the bottle-detached guard is applied around the eye. The frictional or wedge-fit seating of the nipple 14 within the conically-surfaced margins of the holes in the cap 3, guard 1 and bulb 15 serves to hold the named parts clamped together while permitting their convenient and expeditious separation for cleaning as well as their economical original assembly.

10 In the modification of Figure 4, a bottle neck 18 is externally plain and adapted to receive interiorly a somewhat yielding stopper 19 having a small central duct 20 and integral with a guard 15 21 provided only with a pair of oppositely disposed vent holes 22. Above the central portion there is another tapered extension 23 intended to be frictionally insertible or slipped off of a rubber bulb 24 having the hole 25. A shoulder 20 on the reinforced lower end of the bulb abuts at 26 the upper surface of the integral eye cup and stopper.

25 Figure 5 illustrates a bottle or container neck 27 as again externally threaded at 28 for screw-threaded envelopment by a molded hard rubber or suitable plastic composition cap 29 integral with a flaring eye-surrounding guard 30 while the hollow cap 29 is interiorly threaded at 31. Centrally, the unitary cap and guard is provided with 30 a screw-threaded opening 32 in which may be detachably fitted any type of screw plug 33. Gaskets 34 and 35 may be interposed between the rim of the bottle neck and head of the cap and between the upper margin of the hole 32 and plug 35 shoulder respectively. This modification embodies one of the primary features of my origination, namely, the advantageous unitary assembly of a screw cap and eye cup or guard, both by themselves long since known and used separately, 40 but never to my knowledge so combined for cooperative association with a bottle and coaction either with a syringe or eye dropper with the discharge nozzle of either projected through the opening 32 when the plug 33 has been removed.

45 I claim:

1. The combination of a hollow internally threaded cap for a bottle top, a larger eye guard having its central portion secured to the head of said cap and in its entirety enclosing the latter in 50 spaced relation thereto and a syringe structure provided with a nozzle projecting through both cap and guard, said structure further provided with flanges respectively abutting the relatively remote sides of the attached portions of said cap and guard.

55 2. In combination, an eye cup, a rubber nipple extending therethrough and provided with differently directed projections, a syringe detachably secured to one of said projections and a bottle cap comprising a head surrounding and abutting the other one of said projections, said cap further comprising one annular flange projecting toward the open end of said eye cup and interiorly provided with screw threads for attachment around the neck of a bottle.

60 3. In combination as an appliance adapted to be carried by a container, an eye cup having a perforated flat bottom and a cap for said container, said cap having a flat head interiorly secured to the bottom of said guard and the concave sides of both guard and closure being similarly directed.

65 4. In an appliance adapted to be attached to a bottle having an exteriorly threaded neck, the combination of a shell-like guard intended for

70 pressure application around an eye and a hollow screw cap adapted for cooperation with said bottle neck, the head of said cap conforming and being secured to the bottom of said guard interiorly of the latter, the concave sides of both guard and cap being correspondingly directed and the cap considerably spaced from the margin of the guard, said guard and cap being provided centrally with registering apertures and means for closing the latter, comprising a flange exteriorly abutting the 75 outer side of the bottom of the guard and another flange interiorly abutting the inner side of the head of said cap.

80 5. In combination, a bottle cap, an eye cup and a bulb having registering holes respectively defined by walls which are merging portions of the same frusto-conical surface and a nipple frictionally seated in all of said holes, said cap and eye cup having their open ends facing in the same direction with the former within the confines of the latter.

85 6. In combination, an eye cup having a bottom provided with an opening, a structure comprising a nipple occupying said opening and provided with a flange larger than said opening and interiorly of said eye cup, said structure further comprising a rubber bulb located exteriorly of said eye cup and having a margin abutting the bottom of the latter whereby relative movement between cup and structure in both axial directions is prevented.

90 7. In combination, an eye cup having a flat bottom provided with an opening, a structure comprising a nipple occupying said opening and provided with a flange larger than said opening and interiorly of said eye cup, said structure further comprising a rubber bulb located exteriorly of said eye cup and having a flat margin abutting the latter whereby relative movement in both axial directions is prevented, and a lining tube 40 extending through said nipple and provided with a flange within said bulb which flange is larger than the opening in the nipple.

95 8. In combination, a bottle having an exteriorly threaded neck, an eye cup fashioned with a central opening, an interiorly threaded and centrally perforated bottle cap fitted to said bottle neck and communicating through said opening, a flanged nipple projecting through both cup and cap and a syringe attached to a projecting end of 50 said nipple and cooperating with said nipple flange to clamp said cup and cap therebetween.

100 9. In combination, for coaction with a container having an exteriorly threaded entry, a complementarily screw-threaded and centrally apertured cap for said entry, a concavo-convex guard adapted to enclose the human eye and enclosing said cap, said guard being provided with a central aperture registering with said cap aperture and a syringe closing said registering apertures when the entire combination is carried by a container, said syringe being adapted to communicate through both cap and guard.

105 10. The combination of a structure comprising a hollow internally threaded cap to serve as an attachment to the neck of a container, an elliptical, concavo-convex eye guard enclosing and secured to said cap, the margin of said guard being concave and extending beyond the margin of said cap, the center of said structure being provided with an aperture and a syringe structure for closing said aperture when the entire combination is carried on a container.
